STANLEY W. NICHOLSON, OF TOLEDO, OHIO, ASSIGNOR TO THE MILBURN WAGON COMPANY, OF TOLEDO, OHIO, A CORPORATION OF OHIO.

WINDOW RAISING AND LOWERING MEANS.

1,183,901.

Specification of Letters Patent.

Patented May 23, 1916.

Application filed April 24, 1914. Serial No. 834,096.

To all whom it may concern:

Be it known that I, STANLEY W. NICHOLSON, a citizen of the United States, and a resident of Toledo, in the county of Lucas and State of Ohio, have invented a certain new and useful Window Raising and Lowering Means; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to means for controlling the raising and lowering of windows, but is not restricted to such use as it may be used in any connection for which it may be adapted or appropriate.

The object of my invention is the provision of means of the character described which is simple and inexpensive in its construction, is easily operated to raise or lower the associated window, and is particularly adapted for use in connection with the type of windows commonly used in closed automobiles and other vehicles, which windows have lowering movements when being opened.

A further object of my invention is the provision of a means of the character described, which is automatically locked in any position of its window raising or lowering movement where it is permitted to rest when the pressure exerted by the raising or lowering action is released from the control means.

The invention is fully described in the following specification, and while, in its broader aspect, it is capable of embodiment in numerous forms, a preferred embodiment thereof is illustrated in the accompanying drawings, in which,—

Figure 1 is an inner side elevation of a vehicle door with the invention associated therewith and with the window partly lowered. Fig. 2 is an enlarged detail of the invention, with parts broken away and with the operating handle removed. Fig. 3 is a section on the line α , α in Fig. 2, with parts in full. Fig. 4 is an enlarged cross-section of a portion of the door taken above the window raising and lowering means thereof, and Fig. 5 is an enlarged inner side view of

the control handle removed from the parts with which it is associated.

Referring to the drawings, 1, in the present instance, designates a vehicle door having a window opening 2 therein, and 3 designates a glass or window part which is adapted to stand in position to close the opening 2 or to be lowered into the lower portion of the door, which is made hollow for such purpose, as is customary in doors 65 commonly used in closed vehicles, such for instance, as automobiles.

The window or member 3 is intended to rest freely at its lower edge on a roller 4, which is carried at the free end of a vertically swinging arm 5, said arm being provided adjacent to its inner end with a journal or trunnion part 6 that is mounted for pivotal movements in a bearing bracket 7. The arm 5 and bracket 7 are disposed within 75 the hollow or lower portion of the door 1, and the bracket is bolted or otherwise suitably secured to the inner side of one of the upright casing members 8 of the door, as shown in Figs. 1 and 4, in position for the 80 arm 5 to project widthwise of the door within the hollow portion thereof into which hollow portion the window or member 3 has its lowering movements. It is evident that a swinging of the arm 5 will 85 cause the roller 4 to travel along the lower edge of the window or member 3 and to effect or permit a raising or lowering of such member as the case may be.

The journal or trunnion portion 6 of the 90 arm 5 is provided transversely thereof with two parallel sockets 9, one at each side of the trunnion axis, and each terminating at one end short of the adjacent side of the trunnion, as shown in Figs. 2 and 3. In 95 each of the sockets 9 is mounted a dog 10, which is adapted to have reciprocal movements longitudinally of the socket, and is provided at its outer end with a tooth 11, which is adapted to project into a registering one of a series of notches 12 provided within the wall of the journal receiving opening of the bracket. A coiled compression-spring 13 is disposed within the inner end of each socket and has one end thrust 100 against the inner end of the associated dog 10 to urge an outward movement of the dog to force the tooth 11 into a registering one of the notches 12. Each of the teeth 11 of the two dogs is beveled at one side thereof to 110

5 permit a turning of the journal or trunnion part 6 in one direction relative to the bracket 7 without withdrawing the dog from notch engaging position. The beveled sides of the teeth 11 are reversely positioned however, with respect to the turning movements of the trunnion 6 so that one dog normally locks the trunnion from turning in one direction and the other dog normally locks the trunnion against a turning in the other direction relative to the bracket 7. In the present instance, the teeth 11 have their inner or adjacent sides beveled.

10 The swinging movements of the arm 5 and the releasing movements of the respective dogs 10 from engagement with the notches 12 of the bracket member are controlled by a controlling handle 14, which is mounted for free turning movements on a 15 pivot stud 15 projecting axially from one end of the journal or trunnion part 6, said handle, in the present instance, being disposed at the inner side of the bar 1. The handle 14 is retained in loose pivotal engagement with the stud 15 by a screw 16 or in any other suitable manner.

20 The handle 14 is provided at the inner side of its inner end portion in concentric relation to the stud 15 with a segmental 25 boss or projection 17, which projects through a registering segmental slot 18 in the adjacent end of the trunnion part 6, as shown in Fig. 3 and by dotted lines in Fig. 2. The boss 17 is of less length than the slot 18 to permit the handle 14 to have 30 limited rocking movements relative to the trunnion part 6. When the handle has been rocked a sufficient distance to place either 35 end of its boss 17 in contact with the respective end wall of the slot 18 a continued 40 rocking movement of the handle will impart a rocking movement in the same direction to the trunnion part 6 and arm 5. A pin 19 projects outwardly from each dog 45 10 into the respective end portion of the slot 18 and in the path of movement of the respective end of the boss 17, whereby the boss 17 when rocked in either direction will 50 act against the pin 19 toward which it is being rocked and effect a sufficient movement of such pin and the attached dog to 55 withdraw the associated tooth 11 from notch engaging position before the end of the boss has moved into thrust contact with the respective end wall of the slot 18. When the 60 pin 19 has moved from normal position it enters a registering notch 20 in the respective end wall of the slot 18. It is thus 65 evident that a movement of the handle 14 to effect a swinging of the arm 5 in either direction first moves to released position 70 a pawl 10, which locks the arm against swinging in the desired direction, and then 75 positively swings the arm, the other pawl 80 10 of the set riding freely over the serrated

or notched surface of the bracket opening 7 during such movement. Upon a releasing of the handle it moves to neutral position under the tension of the springs 13 acting against the pawls 10 and permits both pawls 75 to have locking engagement with the bracket member, thus holding the arm 5 in adjusted position.

80 The weight of the window or member 3 on the arm 5 is counter-balanced, in the present instance, by a coiled contractile spring 21, one end of which is fixed, as at 22, at one side of the swinging axis of the arm to a segmental plate 23, which encircles one-half of the trunnion part 6 around the 85 bracket bearing, and is bolted or otherwise suitably fixed at its ends to the arm 5, as at 24 (Fig. 2). The other end of the spring 21 is fixed, as at 25, to the opposite edge portion of the door 1, or to any other suitable anchoring means within the door. The arm 5, in the present instance, is shown as being removably secured in a fixed manner, as by a screw 26, to the opposite end of the trunnion part 6 from the handle 14 and 90 as having a long and a short arm projecting in opposite directions from said trunnions, the short arm being provided to form an attaching means for the respective end of the segmental plate 23.

95 It is evident that I have provided a simple and efficient means for controlling the raising and lowering of a vertically movable window or similar member and that such means is adapted to lock the window at any 100 point in its range of movement, the locking means being automatically released by the control handle upon an initial movement thereof after which a continuing of the movement of the control handle effects 105 a desired swinging of the window-engaging arm.

110 I wish it understood that my invention is not limited to any specific construction or arrangement of the parts, as it is capable of numerous modifications without departing from the spirit thereof. It is also understood that while I have illustrated a particular form of locking means in connection with my invention, that other forms 115 of locking means suitable for the purpose may be employed if desired.

120 Having thus described my invention, what I claim as new, and desire to secure by Letters Patent, is—

1. In combination, a bearing member having an opening therein with its wall provided with an annular series of teeth, a trunnion part journaled in the opening of the bearing member and formed with a pair 125 of sockets, spring actuated dogs slidable in the sockets of the trunnion part and adapted for engagement with the teeth of the member, a pin on each dog extending axially of the trunnion part, and a handle rock-

ingly mounted on the trunnion part to engage with either pin for sliding the corresponding dog against the action of its spring.

5. 2. In combination, a bearing member having an opening therein with its wall provided with an annular series of teeth, a swinging arm having a trunnion part journaled in said opening, said trunnion part 10 having a bearing stud projecting coaxially from one side thereof, a pair of parallel recesses provided in said trunnion part transversely of its axis and one at each side thereof, a dog mounted in each recess for reciprocating movements therein and adapted to engage at their outer ends with said series of teeth, one dog engaging with the teeth in a manner to permit rotation of the trunnion part in one direction and the other dog 15 engaging with the teeth in a manner to permit rotation of the trunnion part in the opposite direction, a spring mounted in the base portion of each recess and urging an outward movement of the associated dog, 20 and a handle mounted on said stud for limited rocking movements relative thereto and operable when rocked in one direction relative to the stud to engage and release one dog to permit a turning of the trunnion 25 part in the direction for which it is re- ced, and vice versa.

3. In combination, a bearing member having an opening therein with its wall provided with an annular series of teeth, a 35 trunnion part journaled in the opening of the bearing member and formed with a pair of sockets and a segmental opening leading to the latter, a spring-actuated dog in each socket of the part adapted for engaging 40 with the teeth of the member, and a handle having a segmental projection operable in the segmental opening of the part for engagement with either dog to move the latter against the action of its spring.

45. 4. In combination, a bearing member having an opening therein with its wall provided with an annular series of teeth, a trunnion part journaled in the opening of the bearing member and formed with a pair 50 of sockets and a segmental opening leading to the latter, a spring-actuated dog in each socket of the part adapted for engaging with the teeth of the member, an axially extending stud on the part, and a handle rock- 55 ably on the stud and having a projection operable in the segmental opening of the

part for engagement with either dog to move the latter against the action of its spring.

5. In combination, a bearing member having an opening and a series of teeth about the opening, a trunnion part journaled in the opening of the bearing member, a pair of dogs movably mounted on the part for engaging the teeth of the member, a handle 60 rockably mounted on one side of the trunnion part for engaging either dog to disengage it from the teeth of said member, and an arm secured to the opposite side of the trunnion part and across the bearing 65 member.

6. In combination, a bearing member having an opening and a series of teeth about the opening, a trunnion part journaled in the opening of the bearing member, a pair 75 of dogs movably mounted on the part for engaging the teeth of the member, a handle rockably mounted on one side of the trunnion part for engaging either dog to disengage it from the teeth of said member, 80 an arm secured between its ends to the opposite side of the part, a segmental plate concentric with the latter and having its ends secured to the arm on each side of the point at which it is secured to the part, and a 85 spring having one end secured to the plate and its opposite end adapted for being anchored to a fixed part.

7. In combination, a bearing member having an opening therein with its wall provided with an annular series of teeth, a trunnion part journaled in the opening of the bearing member and formed with a pair of parallel sockets and a segmental opening 90 communicating therewith, a stud extending axially from the trunnion part, a spring actuated dog in each socket having a lateral pin and adapted to engage the teeth of the bearing member, and a handle rockable 95 on the stud and provided with a projection 100 adapted for movement toward either end wall of the segmental opening and engage either pin of the dogs to release the dog from the teeth of the member.

In testimony whereof, I have hereunto 105 signed my name to this specification in the presence of two subscribing witnesses.

STANLEY W. NICHOLSON.
